UNITED STATES PATENT OFFICE.

GUSTAF JOHNSON, OF CHICAGO, ILLINOIS.

CARBURETING APPARATUS.

959,350.

Specification of Letters Patent. Patented May 24, 1910.

Application filed June 1, 1908. Serial No. 435,966.

To all whom it may concern:

Be it known that I, GUSTAF JOHNSON, a citizen of the United States, residing at Chicago, in the county of Cook and State of Illinois, have invented certain new and useful Improvements in Carbureting Apparatus, of which the following is a specification.

This invention relates to improvements in that class of machines employed for producing carbureted air from hydro-carbon oils, such as gasolene, and it consists in certain peculiarities of the construction, novel arrangement, and operation of the various parts thereof, as will be hereinafter more fully set forth and specifically claimed.

The principal object of the invention is to provide a carbureting apparatus which shall be simple and inexpensive in construction, strong, durable and effective in operation, the parts of which shall be so made and arranged with respect to one another that a very small quantity of gasolene, which as is well known is highly explosive, will be contained in the machine and on the premises, yet it will be automatically supplied through the machine in sufficient or the desired quantities for carbureting.

Another object of the invention is to provide improved means for charging air with the volatilized hydro-carbons to the end that illuminating carbureted air of the highest quality may be produced or afforded, and so that it may be delivered to the service pipes in a dry and pure condition and as required.

Numerous other objects and advantages of the invention will be disclosed in the subjoined description and explanation.

In order to enable others skilled in the art to which my invention pertains, to make and use the same, I will now proceed to describe it, referring to the accompanying drawings, in which—

Figure 1 is a vertical central sectional view of a carbureting apparatus embodying the invention; Fig. 2 is a sectional view taken on line 2—2 of Fig. 1 looking in the direction indicated by the arrows, showing a part of the water tank and the air feeder or compressor located therein; Fig. 3 is a rear end view of the machine; Fig. 4 is a front view thereof; Fig. 5 is an end view of a portion of the air feeder or compressor, showing it detached from the water tank; Fig. 6 is a vertical sectional view of the carbureter; Fig. 7 is a cross-sectional view

thereof taken on line 7—7 of Fig. 6 looking in the direction indicated by the arrows; Fig. 8 is an end view of the air feeder; Fig. 9 is a cross-sectional view thereof; Fig. 10 is a detached perspective view of one of the partitions of the air feeder, showing it shortened for the convenience of illustration; Fig. 11 is a view in elevation of the air feeder, showing it shortened and illustrating by dotted lines the position of the parts of the partitions which form compartments in said feeder; and Fig. 12 is a vertical sectional view of the pump used for supplying gasolene to the carbureter.

Like numerals of reference, refer to corresponding parts throughout the different views of the drawings.

The reference numeral 15 designates a tank which may be made of any suitable size, form and material, but preferably of metal and with its lower portion semi-circular in shape. This tank may be mounted on supports 16, one of which is located near each of its ends, as shown in the different views of the drawings. Secured to the inner surface of one of the ends of the tank 15 is a journal-box 17 which receives one end of a shaft 18 which is horizontally and longitudinally located in the tank and has its other end fitted in one end of a sleeve 19 which is rotatably mounted on a tubular shaft 20 which is journaled in the opposite end of the tank from that to which the bearing 17 is secured. Extending from the sleeve 19 and communicating with the cavity thereof is a tube 21 which has its free end open, as will be clearly understood by reference to Fig. 1 of the drawings. Mounted on the shaft 18 near each of its ends is a disk 22, each of which is provided with a series of radial slots 23 to receive partitions 24 which are radially disposed with reference to the shaft 18 and in such a manner that their inner edges will be located at a slight distance from said shaft. Each of the partitions 24 has at its ends oppositely extended wings or flanges 25 which will overlap each other, yet will be slightly spaced apart so as to permit the passage of air therebetween to and from the compartments 26 formed by the partitions. Surrounding the partitions 24 and secured to their peripheries is a cylinder 27 which has its end adjacent to the tube 21 closed as at 28, so that, as the air passes from the compartments 26 between the flanges 25 at said end

of the cylinder, it will be caused to enter the tube 21 and pass from the same into the air-
ometer.

By reference to Fig. 1 it will be seen that 5 the cylinder 27 of the air feeder or com-
pressor, which is designated as a whole by
the reference numeral 29, overlaps the ends
of the partitions 24 adjacent to the tube 21,
thus forming a chamber between the end 28
10 of the cylinder and the flanges 25 adjacent
thereto. The rear upper portion of the tank
15 is provided with a cover or housing 30
which extends to about the middle thereof
and has journaled on its upper front portion
one end of a shaft 31 the other end of which
20 is journaled on a support 32 secured to the
front portion of the tank. This shaft has
mounted thereon a drum 33, and is provided
at its outer end with means 34 to engage a
25 crank when it is desired to turn the drum in
order to wind up the cable 35 which is se-
cured at one of its ends to the drum and
passes over a pulley 36 suitably journaled
25 on a hanger 37, and has at its other end a
weight 38 to actuate the drum 33 and
through it and its gearing the air feeder 29.
Mounted on the shaft 18 near its front end
is a gear 39 which meshes with a gear 40
loosely mounted on the shaft 31 near its
30 outer end. Rigidly mounted on the shaft 31
on one side of the gear 40 is a ratchet
wheel 42 and on the other side another
ratchet wheel 43 with which pawls 45 are
adapted to engage. Journaled on the sup-
35 port 32 and to one side of the shaft 31 so as
to mesh with the gear 40 is a pinion 46
which carries a slotted arm 47 in which is
adjustably secured a pin 48 on the upper
end of a pitman 49 which is pivotally con-
40 nected at its lower end to a piston-rod 50
which is pivotally secured at its lower end to
a piston 51 located in a pump cylinder 52,
which pump or cylinder communicates
through a coupling 53 with a valve-casing 54
45 which is provided with a series of valve-
seats 55 and 56, each having a valve 57 and
58, respectively. By reference to Fig. 12 it
will be seen that the valve-seats 55 are ar-
ranged below the support 53 which com-
50 municates with the pumping cylinder 52,
while the valves 56 and seats therefor are
located above the same.

The lower portion of the valve-casing 54
has communication through a pipe 59 with
55 the gasoline tank 60 which may be located
at any suitable point and at any distance
from the machine or premises, and usually
below the surface of the ground for the
sake of safety against explosion. The up-
60 per portion of the valve-casing 54 has com-
munication through a pipe 61 and a cou-
pling 62 with the carbureter 63, which is
preferably mounted on the upper portion of
the cover 30 of the water tank. The lower
65 portion of the carbureter has leading there-

from a pipe 64 which also communicates
with the gasoline tank 60, and is for the pur-
pose of conveying the excess of gasoline or
oil to said tank.

As is clearly shown in Figs. 6 and 7 of 70
the drawings, the carbureter consists of a
vessel of any suitable size, form and ma-
terial, but preferably of metal and rectangu-
lar in shape, and has in its upper portion an
inlet opening 65 for the supply of air there-
to, as well as the opening or coupling 62
75 for the admission of gasoline. Located
within the receptacle 63 are a series of
baffle-plates or shelves 66 which are alter-
nately inclined in opposite directions, as 80
shown, and each of said plates has its free
end upturned as at 67 to form troughs or
receptacles to prevent the gasoline flowing
from said shelves or plates too rapidly, for
it will be understood that said plates or 85
shelves extend from one side of the recepta-
cle 63 to the other side thereof and alter-
nately from one end of the receptacle to
near the other end thereof, thus providing
90 spaces between the alternate ends of the
shelves and the ends of the receptacle. Each
of the shelves 66 is supplied on its upper
surface with a quantity of absorbent ma-
terial 68, such as felt, batting, asbestos or
the like, to absorb and retain gasoline. 95

Suitably mounted near the carbureter 63
is an airometer, which is indicated as a
whole by the reference numeral 69, and
which consists of a vessel 70 having its up-
per end open and provided with a spout 71 100
through which water may be passed to said
vessel. The bottom of the vessel 70 has
communication through a pipe 72 and a
coupling 73 with the tubular shaft 20 of
the air feeder, and said coupling may be 105
provided with a valve or cock 74 for the
discharge of water. Extending upwardly
from the bottom of the vessel 70 and com-
municating with the pipe 72 is a tube 75
which has in its upper end a valve-seat 76 110
for the valve 77 on the lower end of a rod
78 which depends centrally from the top
of a tank 79 which has its bottom open and
is movably located in the vessel 70, so that
the open end thereof will be sealed by the 115
water contained in said vessel. The lower
end of the tank 79 is preferably provided
with weights 80 secured thereto in any suit-
able manner. Communicating with the
lower portion of the receptacle 70 of the 120
airometer and usually through the bottom
thereof is a pipe 81 which leads to and com-
municates through the coupling 65 with the
top of the carbureter. This pipe 81 has
leading therefrom a pipe 82 which commu-
nicates with a pipe 83, which affords com-
munication between the lower portion of the
carbureter 63 and the bottom of a combined
filter and mixer 84, which may be made of
any suitable size, form and material, and 125

may be supported near the carbureter in any suitable manner. The filter or mixer 84 is supplied with a quantity of asbestos, excelsior 85, or other suitable material, and has communicating with its upper end a service-pipe 86 which may lead to the various points at which gas is desired.

From the foregoing and by reference to the drawings it will be readily understood 10 and clearly seen that, by supplying water to the tank 15 which may be done through a supply pipe 87 located in one end thereof so that the water level will be at a point 15 above the shaft 18, the air feeder or compressor 29 may be caused to rotate by reason of the action of the weight 38, the cable 35, drum 33 and gearing between the shaft of said drum and the shaft 18 on which the air compressor is mounted. In this operation it is apparent that in the rotation of the cylinder 27 air will be caused to enter the compartments 26 of the compressor above the water level and between the flanges 25 at that end of the compressor adjacent to the 25 pump. As the compressor cylinder rotates farther it will be understood that the air will pass from the compartment which is being submerged into the chamber of the cylinder at the end thereof in which the 30 tube 21 is located between the flanges 25 and said end, and will be caused to enter the tube 21 and to pass therefrom into the airometer.

In the foregoing operation the piston 51 of the pump will be reciprocated, thus alternately opening and closing the valves 57 and 58, thereby drawing gasoline from the tank 60 through the pipe 59 into the valve-easing 54, and from thence through the pipe 61 40 into the top of the carbureter where it will fall onto the upper baffle-plate and pass from the same to the lower ones, in which operation it will be suspended by reason of the absorbent material located on said plates 45 or shelves to the end that evaporation may take place and a thorough carbureting process carried out, for it will be understood that air from the airometer will at the same time be supplied to the carbureter through the 50 pipe 81, which, as before stated, leads from the lower portion of the airometer.

It is evident that the pump will be driven through the instrumentality of the gear 40, pinion 46, pitman 49 and piston 51, which 55 parts are actuated by the weight 38, cable 35 and drum 33. The carbureted air, as it passes from the carbureter through the pipe 83 into the mixer or filter 84, may have additional air added thereto through the 60 pipe 82 which leads from the airometer, and as the carbureted air enters the mixer or filter 84 it is evident that it will undergo still further commingling, and as it passes through the material contained in the mixer 65 84 will be delivered to the service pipe 86

in a pure and dry state ready for consumption.

By the arrangement of the parts it is obvious that it will be necessary to maintain only a very small quantity of gasoline within the carbureter, as it will be disposed in such a manner, by reason of the baffle-plates or shelves, as to evaporate quickly and thoroughly commingle or charge the air with volatilized carbon. As the free end of each 75 of the baffle-plates 66 is upturned to provide a trough on each of the shelves, it is apparent that the liquid will be held thereon so as to keep the absorbent material saturated, but that the surplus liquid will pass 80 over the upper parts of said upturned portions from one shelf to another until it reaches the bottom of the receptacle, from whence it will pass through the pipe 64 back into the tank 60 or source of supply, and thereby 85 prevent waste of material, and by this continuous passage of the gasoline avoiding possibility of explosions, on the premises.

Having thus fully described my invention, 90 what I claim as new, and desire to secure by Letters-Patent, is—

1. A carbureting apparatus comprising, in combination with an air compressor, a housing secured to the top of the compressor at 95 one end thereof, an airometer having its bottom secured to the outer end of said housing, a connection between the air compressor and the airometer, a carbureter supported on said housing adjacent said airometer, a connection between the top of the carbureter and said airometer, a gasoline tank, a connection between the bottom of said carbureter and said tank, means carried by one end of said air compressor for conveying 100 gasoline from the tank to the carbureter, and means on the air compressor arranged between the housing and the adjacent end of the air compressor for operating the gasoline conveying means and the air compressor. 110

2. A carbureting apparatus, comprising, in combination with an air compressor, a housing secured to the top of the air compressor at one end thereof, an airometer supported on the housing, a carbureter also supported on the housing and in communication with the airometer, means on the opposite end of the air compressor for supplying gasoline to the carbureter, and means supported from said housing and the air 120 compressor and arranged on the latter in the space between the housing and the adjacent end of the air compressor for operating the latter and said gasoline supplying means.

GUSTAF JOHNSON.
